(57) **CLAIM**

The ornamental design for a tripod system, as shown and described.

DESCRIPTION

FIG. 1 is a front right isometric view of the tripod system showing the new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top plan view thereof;

FIG. 7 is a bottom plan view thereof.

FIG. 8 is a front right isometric view of an alternate arrangement of the tripod system of FIGS. 1-7;

FIG. 9 is a front side elevation view thereof;

FIG. 10 is a rear side elevation view thereof;

FIG. 11 is a left side elevation view thereof;

FIG. 12 is a right side elevation view thereof;

FIG. 13 is a top plan view thereof;

FIG. 14 is a bottom plan view thereof.

FIG. 15 is a front right isometric view of a tripod system as in FIGS. 1-7 in a folded up arrangement;

FIG. 16 is a front side elevation view thereof;

FIG. 17 is a rear side elevation view thereof;

FIG. 18 is a left side elevation view thereof;

FIG. 19 is a right side elevation view thereof;

FIG. 20 is a top plan view thereof; and,

FIG. 21 is a bottom plan view thereof.

The broken lines in 8-16, 18, 19 and 21 depict environmental subject matter and unclaimed portions of the tripod system only and form no part of the claimed design.
